UNITED STATES PATENT OFFICE

158,205

EARRING DISPLAY CASE

Albert H. Leissing, Franklin, Mass.

Application May 18, 1948, Serial No. 146,439

Term of patent 14 years

(Cl. D30—5)

To all whom it may concern:

Be it known that I, Albert H. Leissing, a citizen of the United States, residing at Franklin, in the county of Norfolk and State of Massachusetts, have invented a new, original, and ornamental Design for an Earring Display Case, of which the following is a specification, reference being had to the accompanying drawing, forming part thereof.

Fig. 1 is a perspective view of an earring display case, showing my new design and with the cover partially raised;

Fig. 2 is a side elevational view with a portion of the cover broken away; and

Fig. 3 is a front elevational view thereof.

I claim:

The ornamental design for an earring display case, as shown.

ALBERT H. LEISSING.
